Primary Examiner — Brian N Vinson**CLAIM**

(57) The ornamental design for a holder for a cleaning implement, as shown and described.

DESCRIPTION

FIG. 1 is a top, front, left perspective view of a holder for a cleaning implement our new design;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof; and,

FIG. 8 is a top, front left perspective view in an opened position thereof.

The broken line disclosure in the views represents unclaimed portions of the holder and a cleaning implement which is shown for illustrative purposes only.
